UNITED STATES PATENT OFFICE.

GEORGE HENDERSON, OF DORCHESTER, MASSACHUSETTS.

CONTAINER.

Application filed January 18, 1922. Serial No. 530,201.

To all whom it may concern:

Be it known that I, GEORGE HENDERSON, a citizen of the United States, residing at Dorchester, county of Suffolk, Commonwealth 5 of Massachusetts, have invented certain new and useful Improvements in Containers, of which the following is a specification.

This invention relates to dispensing vessels for poultry and the like, and particularly to 10 feed or water dishes in which food or drink is openly displayed and intended to be freely accessible.

Devices of this sort have come into such general use as to constitute a standard type 15 of well known utility but having certain general faults.

These faults are for the most part due to the general open character of the vessel. They are for the most part incident to the 20 tendency of the birds to get into the dish and scratch and spill or foul the contents.

Experience has shown that the most satisfactory material for such vessels is pottery. Metal vessels either succumb to rust or if 25 galvanized or otherwise treated are apt to poison chicks or younger fowl.

The difficulty with pottery vessels lies primarily in their frangibility in any exposed projection or recess such as handles or ears 30 or bosses for handles. The ideal feed dish is therefore plain and substantial and with a minimum of excrescence.

In accordance with my invention I have 35 provided a container of the utmost simplicity in combination with an equally simple lifting and guarding element which gives an inexpensive device of great practical utility and serviceability.

As illustrative of my invention I have 40 shown such a device in the accompanying drawings to which I will make reference through the usual reference characters and in which:

Fig. 1 is a plan view of my lift and guard 45 member.

Fig. 2 a side view of the same.

Fig. 3 a side elevation of a vessel with the lift and guard about to be applied.

Fig. 4 the same with the device in place.

Fig. 5 is a view of another form of lift and guard, and

Figs. 6 and 7 are enlarged details of the ends of the guard arms.

My crock or containing vessel C is preferably a simple cylindrical container of medium height but having about its upper edge

a lip or external bead L of substantial overhang so as to form a shoulder l and of depth sufficient to bring the plane of the shoulder l well below the surface or upper level of the 60 vessel top.

My lift and guard member G is of general cruciform and comprises two crossed double loops or parallel slightly resilient bars g or rods of slightly greater length than the diameter of the vessel. These rod pairs are soldered or otherwise firmly joined at their crossings centrally of each other and thus centrally of the container C. At their outer ends the rod pairs g are bent downwardly as 65 at h and then inwardly and again outwardly as at i to form a spring lip adapted to engage the shoulder l.

The member G therefore has a firm engagement with the container at four points 75 spaced 90° apart. In use as a carrier the fingers are hooked under the center of the guard G and the vessel thus lifted or carried. The upward pull of such a lift causes the lips i to draw under and more firmly engage the shoulder l so that there is no possibility of release or slipping.

When the vessel is in the coop or yard and filled the member G forms a sub-dividing guard over the vessel top. In fact the top opening is divided into four segmental spaces thus tending to distribute the feeding fowl about the vessel while giving ample access to the contents. The guard is by its 85 form and the spacing of the bars g ample to prevent the over anxious birds from getting in the dish and the relative disposition of the arms makes such awkward and inconvenient foot hold that the tendency to roost is very 90 slight.

In Fig. 5 I have shown a slightly different form in which the rods g are given a bend as at g' at the edge of the dish so that the main portion of the member G is sunken or depressed just below the top surface of the 100 vessel. This gives an additional grip area and affords a slight clearance of the main portion of the guard below the edges of the top.

Various modifications as to such details 105 and other variations in form and structure may be had, all without departing from the spirit of my invention if within the limits of the appended claims.

What I therefore claim and desire to secure by Letters Patent is:—

1. A combination lift and guard for a

feeding vessel having a shoulder about its mouth, consisting of a member disposed horizontally across the vessel mouth in close juxtaposition thereto and having resilient lips adapted to engage under the vessel shoulder.

2. A combination lift and guard for a feeding vessel having a shoulder about its mouth, consisting of a cruciform member disposed horizontally across the vessel mouth in close juxtaposition thereto and having reversely bent resilient lips adapted to engage under the vessel shoulder.

3. A combination lift and guard for a feeding vessel having a shoulder about its mouth, consisting of a member disposed horizontally across the vessel mouth in close juxtaposition and substantially parallel thereto and having depending attaching portions adapted to bear against the vertical edge of the vessel shoulder, said attaching portions terminating in resilient lips adapted to engage under said shoulder.

4. A combination lift and guard for a feeding vessel having a shoulder about its mouth, consisting of a cruciform member disposed horizontally across the vessel mouth in close juxtaposition thereto, and having depending substantially vertical attaching

portions adapted to bear against the outer vertical edge of the vessel shoulder, said portions terminating in reversely bent resilient lips adapted to engage under said shoulder.

5. A combination lift and guard for a feeding vessel having a shoulder about its mouth, consisting of a member disposed horizontally across the vessel mouth slightly below the plane thereof, and having attaching portions bent upwardly and horizontally and thence downwardly to bear upon respectively the inner, upper and outer faces of the vessel shoulder, and terminating in resilient lips adapted to engage under said shoulder.

6. A combination lift and guard for a feeding vessel having a shoulder about its mouth, consisting of a cruciform member disposed horizontally across the vessel mouth slightly below the plane thereof, and having attaching portions bent upwardly and horizontally and thence downwardly to bear upon respectively the inner, upper and outer faces of the vessel shoulder and terminating in reversely bent resilient lips adapted to engage under said shoulder.

In testimony whereof I affix my signature.

GEORGE HENDERSON.
